PORTABLE SECTIONAL STAIRWAY

Robert E. Reynolds, New Orleans, La., assignor
of one-third to William A. Lurie, and one-
third to Charles B. Anderson, both of New
Orleans, La.

Application October 12, 1938, Serial No. 234,610

5 Claims. (Cl. 72—96)

My invention relates to sectional and portable stairways adapted to be cast in concrete or like cementitious material or to be fabricated from wood or like material.

5. An object of my invention is to produce a portable concrete stair which is adapted to permit variations in the height of the riser elements and variations in the width of its tread during the erection of the stairs.
10. Another object of my invention is to provide box side structures in stairway construction and a means of anchoring the parts of same in assembled relationship.

15. Another object of my invention is to provide reinforced slabs to support the riser elements of my steps and a means of anchoring the reinforced slab to the riser elements in my stairway construction.

20. Another object of my invention is to provide a railing structure for my stairway and a means of detachably locking the railing in its assembled position in the stairway.

25. Other objects of and advantages of my invention will appear during the course of the description of the views illustrating my invention.

In the drawings:

Figure 1 is an isometric front view of my stairway with the side box construction added.

Figure 2 is a cross sectional view through the line 2—2 of Figure 1 with sections of the box construction broken away.

Figure 3 is a broken plan view of my steps with the caps of the side boxes removed, showing means for holding parts assembled.

35. Figure 4 is a detailed cross sectional view of my step construction, showing a variation of the height of the riser.

40. Figure 5 is another detailed cross sectional view of my step construction showing another variation in the height of the riser and showing also a variation in the width of the tread.

45. Figure 6 is an elevation view of a riser element of my stairway with anchoring means for joining the same to reinforcing slabs.

Figure 7 is a side view of my stairs showing the bannister locked in the same.

Figure 8 is an end view of the bannister locked in the stair.

50. Figure 9 is a detailed view of one of the members constituting a locking means for holding the railing in position.

In Figures 1 to 5, numeral 1 designates the stringers of my steps. Numeral 2 designates re-
55. inforging slabs adapted to extend from one

stringer to another and support tread members 3 together with depending riser elements 4.

In working out this invention, I had in mind a problem of designing a portable step structure that can be assembled and disassembled by one man. To accomplish this, I have cast my parts in proportions of weight than can be handled by one man. For example, the combination tread 3 and riser elements 4 can be easily handled by one man. To avoid a weakness because of a light casting, I provided a reinforcing slab 2 designed to go under tread 3 and support the same. The reenforcing slab 2, however, serves the additional function of an adjusting means for varying the effective height of the riser. For example, when one of the slabs is moved, flush against the riser, portions of the stringer, the next succeeding tread 3 and riser 4 combination can be set up on the slab 2 to give an increase in effective riser height equal to the thickness of slab 2. In this respect, see Figure 4. Where this adjustment is made, it is necessary to block up under the next succeeding slab to raise it in proper position to support its overlying tread 3.

If a greater effective riser height is desired, a riser combination 3 and 4 may be set up on top of the lower tread 3. See Figure 5. This will give an effective increase in riser heights equal to the thickness of the slab plus the thickness of the tread. Where it is desirable to narrow the width, of the tread, the above described adjustment is used.

It is found in practice that the height of porches which my portable steps are designed to serve vary several inches. This variation does not produce any serious difficulty in the installation of my steps because of the fact that I may easily adjust my steps as described above, to fit nicely with the porch or door sill it serves.

Referring again to Figure 1, numeral 10 designates generally the side box construction forming a part of my invention. These side boxes 10 serve admirably as seats for people to sit on. This style of stair with side boxes is in common use and very popular in New Orleans and many other cities. A description of the box structure of my invention will appear from my description of its assembly. Wherein, I say that I first place the vertical sides of the boxes 11 up against the riser 1 of my stair. Then I place the outer 40 parallel vertical walls 12 in proper spaced relationship to receive the lower end pieces and upper end pieces 14. The next step is to place wood shutters 15 in place to make well formations to receive fluid concrete. The side mem- 45

bers 11 and 12 and end pieces 13 and 14 are all provided with wire loops 16. The caps 17 which complete the structure are also provided with wire loops, extending from their under surfaces. 5 Now, when the boxes are assembled, the fluid concrete is poured into the wells to fill the same. Then the caps with their depending loops are placed in position. When the poured concrete sets, the wire loops 16 on these box members 10 become frozen into the concrete and serve as anchoring means to hold the respective box members in an assembled position even though the poured concrete does not adhere to the box members themselves.

15 In the modification of my invention illustrated by Figures 6 to 9, numeral 20 designates a stringer. I use here a stringer which has its tread supporting surfaces provided with wire loops 21, under which prongs 22, are attached to tread supporting reenforced slabs 23, adapted to fit. In the assembly of the slab 23 the prongs 22 on the slabs 23 are first worked under the loops 21. The next step in the assembly is to mash the reenforced slab down onto the stringer 20. In doing 25 this, I flatten the loops 21 and prongs 22 in a binding relationship with one another. This bond is helped out by a smear of concrete grouting previously placed on the riser supporting surfaces of the stringer 20. Even though the smear 30 of concrete between the stringer 20 and the reenforcing slab 23 does not hold the metallic bond made by the loops 21 and the prongs 22 will still function to hold the slabs down in place and hold the stringer 20 in correct space relationship 35 against any jarring action. The stringers 20 are provided on their lowermost and uppermost tread supporting surfaces with recesses 24 designed to receive the posts 25 of a bannister structure. The lowermost and uppermost treads 26 are provided 40 with notches 27 designed to nicely fit the posts and assist to hold same in vertical position.

While it is believed that from the foregoing description the nature and advantages of the invention will be readily apparent, I desire to have it understood that I do not limit myself to what 45 is herein illustrated or described, and that such

changes may be resorted to when desired, as fall within the scope of what is claimed.

What I claim is:

1. A stair comprising stringers having horizontal tread supporting surfaces with vertical surfaces joining the said horizontal surfaces, supporting slabs of a diameter less than the said horizontal surfaces mounted on the horizontal surfaces and combination tread and riser elements adjustably mounted on the said supporting 5 slabs whereby to permit adjustments in the effective height of riser element and the effective width in tread elements of the stair.

2. The device as claimed in claim 1, wherein the supporting slabs are adapted to be adjustably mounted on the said horizontal surfaces of the said stringers.

3. In a stair construction the combination of vertical side members provided with wire loops extending inwardly, end vertical members provided with wire loops extending inwardly, shutters vertically placed between the said side member to form walls with the said side members and the said end members, cap members provided with wire loops extending inwardly, the loop on 20 the said side members, the loop on the said end members and the loop on the said cap members, being adapted to be anchored into concrete when 25 poured into the said wells.

4. In a stair construction comprised of assembled stair members, fastening means for joining said members comprising a wire loop extending from one member and a wire prong extending from another member, the prong being adapted 30 to extend under and be clamped by the loop in the assembled position of the stair members.

5. A stair construction including stringers, said stringers being provided with sockets, a railing member provided with posts, said posts being adapted to fit into the said sockets and tread members provided with notches in their ends, 40 the said posts being adapted to fit into the said notches of the said tread members when the treads are assembled, to the said stringers.

ROBERT E. REYNOLDS. 45
